UNITED STATES PATENT OFFICE.

ALOIS KRIŽAN, OF PHILADELPHIA, PENNSYLVANIA.

ICE-CREEPER.

1,375,254.

Specification of Letters Patent. Patented Apr. 19, 1921.

Application filed September 25, 1920. Serial No. 412,656.

To all whom it may concern:

Be it known that I, ALOIS KRIŽAN, a citizen of Jugo-Slavia, residing at Philadelphia, in the county of Philadelphia and 5 State of Pennsylvania, have invented certain new and useful Improvements in Ice-Creepers, of which the following is a specification.

This invention relates to certain new and 10 useful improvements in ice creepers and the object of the invention is to provide a device of this kind which is extremely simple and durable in construction and capable of being easily manipulated for being placed 15 into practical use.

The invention broadly embodies a substantially U-shaped inverted base member with a right and left hand screw disposed longitudinally therebeneath and journaled 20 in the ends thereof, and heel engaging clamps slidably carried by said base member and having threaded connection with the screw whereby turning movement of the latter will cause relative movement of the 25 clamps, the ends or legs of the base member being provided with anti-slipping means for engaging the ice.

Other objects will appear as the nature of the invention is better understood, and the 30 same consists in the novel form, combination and arrangement of parts hereinafter more fully described, shown in the accompanying drawing and claimed.

In the drawing, wherein like reference 35 characters indicate corresponding parts throughout the several views,

Figure 1 is a view partly in side elevation and partly in vertical section of an ice creeper constructed in accordance with the 40 present invention,

Fig. 2 is a top plan view thereof,

Fig. 3 is a horizontal sectional view taken upon line III—III of Fig. 1,

Fig. 4 is an end elevational view of the 45 device shown in Fig. 1,

Fig. 5 is a vertical sectional view taken upon line V—V of Fig. 1,

Fig. 6 is an enlarged perspective view of one end of the base member,

Fig. 7 is a perspective view of one of the 50 toothed calks, and

Fig. 8 is a perspective view of one of the heel engaging clamps.

Referring more in detail to the several 55 views, the present invention embodies a substantially U-shaped inverted base member 5

with the horizontal intermediate portion thereof longitudinally slotted from a point adjacent the center to the ends as at 6, leaving a central connecting web 7. The angular 60 ends or legs of the base member 5 are indicated at 8 and are provided with transverse slots 9 slightly wider than the slots 6 and communicating with the latter, and the intermediate portions 10 of the heel engaging 65 clamps 11 are snugly slidably disposed through the slots 9 beneath the horizontal portion of the base member. The inner end of each clamp 11 is directed downwardly at right angles and centrally provided with a 70 screw threaded aperture 12 having threaded engagement with the adjusting screw 13, one end of which is provided with a left hand screw thread and the other end of which is provided with a right hand screw thread. 75 The outer end of which clamp is bent upwardly and inwardly in the usual manner to provide heel penetrating edges as at 14, and the upwardly extending portion is reduced to provide a neck 15 whereby the base 80 member 5 and clamps 11 are slidably connected. One end of the screw 13 is journaled in an aperture 16 of one of the base member legs, and the other end of said screw freely projects through an aperture 85 17 in the other leg of the base member and is of squared formation as at 18 to receive a suitable wrench or key whereby the screw may be conveniently turned for adjusting 90 the clamps.

As shown clearly in Fig. 6, the lower edges of the legs 8 may be serrated or notched as at 19 so as to provide ice penetrating spurs so as to guard against slipping when the device is used upon the heel of a 95 shoe. However, it is sometimes desirable to use the present device upon the instep portion of the shoe sole just forwardly of the brace of the heel, which requires a greater length to the legs so as to insure engagement 100 of the spurs with the ice while keeping the heel from engaging the latter. In order to provide for this use, split sleeves 20 are clenched upon the legs 8 so as to depend a distance below the lower edges of the latter, and the lower edges of said sleeves are serrated to provide the ice engaging spurs as at 21. The journaled end portion of the screw 13 may pass through the aperture 22 of one of the sleeves 20 as shown in Fig. 1 110 so as to secure said sleeve in place in addition to the clamping of the latter on the leg

of the base member, and the squared end 18 loosely projects through a larger circular aperture 23 in the other sleeve 20. The upper edges of the sleeves 20 are notched or 5 cut away as at 24 for slidable reception of the horizontal portions 10 of the clamps 11.

In using the device, it is merely necessary to rotate the screw 13 in one direction so as to separate the clamps 11 sufficiently to permit the latter to assume a position spaced 10 from the side edges of the shoe sole or heel, after which the screw is rotated in a reverse direction for causing the edges 14 to penetrate the shoe sole or heel, and the device is 15 then securely fastened in position so that the wearer may safely walk upon the ice without danger of slipping by reason of the spurs 19 and 21.

It is believed that the construction and operation as well as the advantages of the 20 present invention will be readily understood and appreciated by those skilled in the art from the foregoing description.

Minor changes may be made therein without departing from the spirit and scope of 25 the invention as claimed.

What is claimed as new is:—

1. An ice creeper embodying a base member of substantially U-shaped inverted form 30 and having longitudinal slots in the horizontal central portion thereof each extending from a point near the center of said central portion to the ends of the latter, the legs of said base member being provided 35 with transverse slots wider than the aforesaid slots and communicating with the latter, a screw journaled longitudinally beneath the central portion of the base member and supported by the legs of the latter, 40 said screw being of right and left hand

form, clamping plates including horizontal portions slidably fitted in the transverse slots of the base member legs and having depending inner ends with the screw threaded therethrough, and means upon the legs of 45 the base member formed for non-slipping engagement with the ice, said last named means including split sleeves clamped upon the legs of the base member and having serrated lower edges. 50

2. An ice creeper embodying a base member of substantially U-shaped inverted form and having longitudinal slots in the horizontal central portion thereof each extending from a point near the center of said central portion to the ends of the latter, the legs of said base member being provided with transverse slots wider than the aforesaid 55 slots and communicating with the latter, a screw journaled longitudinally beneath the central portion of the base member and supported by the legs of the latter, said screw being of right and left hand form, clamping plates including horizontal portions slidably fitted in the transverse slots of the base member legs and having depending inner ends with the screw threaded therethrough, and means upon the legs of the base member formed for non-slipping engagement with the ice, said last named means including 60 split sleeves clamped upon the legs of the base member and having serrated lower edges, said sleeves being further provided with apertures through which the ends of said screw project and having notches in 65 their upper edges slidably receiving the horizontal portions of said clamps. 70

In testimony whereof I affix my signature.

ALOIS KRIŽAN.
